UNITED STATES PATENT OFFICE.

SAMUEL P. LEVENBERG, OF NEW YORK, N. Y

TELEPHONE.

No. 818,698.

Specification of Letters Patent.

Patented April 24, 1906.

Application filed January 16, 1905. Serial No. 241,177.

To all whom it may concern:

Be it known that I, SAMUEL P. LEVENBERG, residing at New York, in the county of New York and State of New York, have invented certain new and useful Improvements in Telephones, of which the following is a full, clear, and exact description, such as will enable others skilled in the art to which it appertains to make and use the same:

10 This invention relates to telephony.

One of the objects thereof is to provide an efficient and compact instrument.

Another object is to provide an instrument of the above type which shall permit of a maximum of convenience in use.

Another object is to provide a simple portable instrument of the above general type which shall amplify the sound-waves to a maximum extent without loss in clearness of speech.

Other objects will be in part obvious and in part pointed out hereinafter.

The invention accordingly consists in the features of construction, combinations of elements, and arrangement of parts, which will be exemplified in the apparatus herein described and the scope of the application of which will be indicated in the following claims.

30 In the accompanying drawings, wherein is shown one of various possible embodiments of my invention, Figure 1 is a sectional elevation of the same. Fig. 2 is a similar view, on an enlarged scale, of a portion of a horn shown in Fig. 1. Fig. 3 is a similar view of the same parts, showing the same in a slightly-different position. Fig. 4 is a sectional view taken substantially on the line $z-z$ of Fig. 2. Fig. 5 is a view of a piece of netting used in the 40 above embodiment of my invention.

Similar reference characters refer to similar parts throughout the several views.

In order to render clearer the general nature of my invention, it may here be noted 45 that in the use of a telephone instrument it is often necessary, particularly during long-distance communication, on account of the limited sphere of efficient action of an ordinary receiver to hold the same to the ear for 50 a considerable period. This is not only tiresome, but involves a considerable waste of time. If it be attempted to avoid this inconvenience by the use of a receiver-support, it is found that the same is clumsy and ineffi-

cient. Also if the receiver is held in a fixed support it is subject to the vibrations of the object upon which the support is fixed, thus interfering with the clearness of the speech emitted.

The above and other defects are obviated 60 in constructions of the nature of that herein described.

Referring now to the drawings, there is shown in Fig. 1 a base 1, having mounted thereon a supporting member or standard 2, 65 which may be detachably secured thereto in any desired manner, as by screws 3. Mounted upon standard 2 are casings 4 and 5, preferably secured to one another by an annular band, as of rubber 6, this band being held in position, as by screws 7. Secured within casing 4 is a cross-piece 8, having mounted thereon a microphone-transmitter 9, which as the same is of well-known construction and forms in itself no part of the present invention will not be described in detail. Upon the outer end of casing 4 is an annular ring 10, 70 having an inwardly-projecting shoulder 11 fitting within the casing.

Mouthpiece 12, which is preferably of soft 80 rubber, is provided with a flange 13, resting against the outer surface of ring 10 and adjustably held in position thereon by means of a collar 14, secured upon the ring. This mouthpiece fits the inner surface of ring 10, 85 thus conducting the voice-vibrations substantially without loss against the transmitter 9, and it may be turned at any angle, being held in the desired position by the frictional engagement of collar 14. The material used for the construction of this mouthpiece is preferably rubber of such composition as to be adapted to retain the desired shape, being aided, if desired, by a stiffening-ring in the face thereof and yet being adapted to be folded against the instrument for purpose of compactness during transportation.

Casing 5 contains a composite magnet 15 provided with a core 16, upon which is wound 100 a coil 17. Magnet 15 is fixed, as by screws 18, within a shell 19, and suitable insulating-blocks 20 and 21 are provided for the purpose hereinafter described. Mounted upon shell 19 is a receiving-diaphragm 22, and a flanged 105 plate 23, formed integral with a receiving-horn 24, has a threaded connection with this shell. A lining 25, preferably of soft rubber,

is interposed between the casing 5 and the shell 19 and between the plate 23 and an outer cap 26 for the purpose of avoiding the transmission of extraneous vibrations to the dia-

5 phragm.

The inner opposing ends of casings 4 and 5 are preferably respectively closed by partitions 27 and 28, having therebetween an air-space 29 for the purpose of aiding in the isolation of one of these casings from the other thereof. Upon the side of partition or wall 28 toward the magnet 15 is a contact-plate 30, connected, as by screw 31, with the framework of transmitter 9. Mounted upon insulating-blocks 20 and 21 are contact-springs 32 and 33, adapted in their normal open-circuit positions to rest against the partition 28, which is of hard rubber or other insulating material. When the horn 24, however, is

10 swung up into operative position, the shell 19, connected therewith, as above described, is turned within lining 25, thus throwing contact springs or brushes 32 and 33 upon the plate 30 and making an electrical connection

15 between the same. The several connections and the wiring of the instrument will be hereinafter referred to.

Horn 24, which, as above indicated, is rotatable, together with the magnet 15 and shell 19, with which it is connected, about a substantially horizontal axis, is adapted to maintain an extended or "operative" position by reason of a slightly-eccentric disposition of the weight of the parts within shell 19 with reference to its axis. This receiving-horn is preferably made substantially of the shape shown, being without sharp turns, so as to avoid loss of clearness of sound, and being of a uniformly-increasing diameter, so as to 20 attain a maximum amplification of the sound-waves. The face of the horn is positioned preferably substantially as shown, being adapted to coat with the ear of the user when talking into mouthpiece 12. By the

25 term "face" as used throughout this description and in the following claims is intended the edges of the open or exposed ends of the members with regard to which it is used.

30 Referring to Fig. 2, it will be seen that the end of horn 24 is provided with an inner lip 34 and that both the inner lip and the outer portion 35 of the horn are provided, respectively, with rings 36 and 37, preferably 35 formed of soft rubber or similar material and adapted to avoid the formation of a gap between the horn and an earpiece 38, mounted between inner lip 34 and the outer portion of the horn and pivotally connected to the

40 same, as shown at 39. Earpiece 38 is preferably formed of hard rubber and terminates in an outer ring 40 of softer material, so as to render the instrument more comfortable in use. A piece of netting 41 is preferably se-

65 cured over the outer surface of the earpiece

38, so as to prevent the entry of dust or other foreign matter into the more delicate parts of the instrument. This netting is in the preferred construction formed of silk or cotton rather than of metal, so as to get the full- 7c est intensity of the speech emitted by the horn.

75 Mounted on casings 4 and 5 is a bell 42 of the ordinary rheotome type connected, as shown, in the ordinary manner across line-wires 43 and 44. As the wiring herein shown is not of the essence of my invention, a description thereof in detail will not be given, it being merely noted that the coil 45 and condenser 46 are positioned within or mounted upon the instrument and that the receiver-circuit is closed by means of contact-springs 32 and 33 and plate 30 when the horn 24 is swung upwardly into operative position.

80 It may here be noted that the expression "sound insulating" is used throughout this description and the following claims in a broad sense as denoting any material adapted to interfere with the transmission of sound-waves.

85 The method of use of the above-described embodiment of my invention is substantially as follows: If it be desired to call another party, the receiver is merely swung up into operative position adjacent the ear of the listener, but not necessarily in contact therewith, as on account of the sound-amplifying qualities of the horn such position is rendered unnecessary. The swinging of the receiver into this position completes the circuit and 90 may be made to call the central office in the well-known manner now in general use. The number having been given, it is necessary merely that the horn be allowed to remain in its upturned position until the party called 95 has responded, the calling party being free to perform other work, being required only to remain in the neighborhood of the instrument. When the called party has answered, the instrument is used in the ordinary manner, excepting that, as above pointed out, it is quite unnecessary to hold the head against the horn or to hold a receiver in contact with the ear in the cramped and uncomfortable, 100 position rendered necessary by the instruments now in general use. If it is desired to prevent persons in the neighborhood from overhearing the message received, it is necessary merely to place the ear against the earpiece 38, the sound being heard then only 105 by the party for which it is intended. When used in this manner, the head is not necessarily held in a fixed position, as the pivoted earpiece 38 allows of any desired movement thereof without the escape of sound. When 110 it is desired to "ring off," the horn is merely thrown into its lower position, whereupon connection is broken without further manipulation of the parts.

115 It will be understood that the mouthpiece 120

12 is in general held in the desired position, adjustment thereof being unnecessary during the use of the instrument.

It will thus be seen that I have provided a simple and efficient instrument which is of inexpensive construction and yet possesses many advantages in use, some of which have been indicated above. It will also be seen that by the use of an instrument made in accordance with the principles of my invention not only is there a material gain in time to the user in view of former constructions, but the same is more comfortable and less confining and cramping than in the case of those instruments which do not possess the features above indicated. It will also be seen that there are no complicated pieces of mechanism used and that the instrument is thus durable and not likely to get out of order when subjected to hard practical use. Also there is a gain not only in the loudness of the sound emitted, but in clearness, as the small voice-waves are amplified without distortion.

As many changes could be made in the above construction and many apparently widely-different embodiments of my invention could be made without departing from the scope thereof, I intend that all matter contained in the above description or shown in the accompanying drawings shall be interpreted as illustrative and not in a limiting sense.

I claim—

1. In telephony, in combination, transmitting mechanism, a member mounted adjacent said transmitting mechanism and provided with an opening, a mouthpiece adapted to fit said opening and provided with a flange resting against said member and an adjustable collar adapted to hold said flange against said member.

2. In telephony, in combination, receiving mechanism, a horn mounted in operative position with relation thereto and an earpiece pivotally mounted upon said horn, parts upon said horn extending inside of and parts surrounding said earpiece.

3. In telephony, in combination, receiving mechanism, a receiving-horn operatively positioned with reference thereto, an earpiece pivotally mounted upon said horn, parts upon said horn extending inside of and parts thereon surrounding said earpiece and flexible bands upon said horn at the points of contact thereof with said earpiece.

4. In telephony, in combination, receiving mechanism, a rotatable sound-amplifying horn of increasing diameter operatively positioned with reference thereto and an earpiece pivotally mounted upon said horn, said horn being provided with means adapted to permit a relative movement of said earpiece and prevent the formation of an opening between itself and the same.

5. In telephony, in combination, a support-

ing member, a casing mounted thereon, receiving mechanism mounted in said casing and a sound-insulating lining within said casing upon which said receiving mechanism is supported and by which said receiving mechanism is surrounded.

6. In a portable telephone, a portable supporting member, two casings mounted thereon, one of said casings containing receiving mechanism and the other containing transmitting mechanism, and a flat band of relatively flexible sound-insulating material embracing and secured to each of said casings and connecting them one with another.

7. In a portable telephone, in combination, a portable supporting member, two casings mounted thereon, one of said casings containing transmitting mechanism and the other of said casings containing receiving mechanism, a horn operatively positioned with reference to said receiving mechanism, and a flat band of sound-insulating material embracing and secured to each of said casings and connecting the same one with another.

8. In telephony, in combination, receiving mechanism comprising a diaphragm, transmitting mechanism, a mouthpiece in operative relation to said transmitting mechanism, and a sound-amplifying horn extending directly from said diaphragm in an unbroken curve of substantially uniformly-increasing diameter, the faces of said horn and said mouthpiece being non-parallel with reference one to another.

9. In telephony, in combination, receiving mechanism, transmitting mechanism, a mouthpiece in operative relation to said transmitting mechanism, and a sound-amplifying horn of substantially uniformly-increasing diameter extending from said receiving mechanism, said horn comprising an earpiece, the exposed edge portions of which are movable with relation to the body of the horn and which is adapted in all operative positions to form an even continuation of the general shape of the body of the horn.

10. In telephony, in combination, receiving mechanism, transmitting mechanism, a mouthpiece in operative relation to said transmitting mechanism, a sound-amplifying horn extending from said receiving mechanism in an unbroken curve of substantially uniformly increasing diameter, said horn comprising an earpiece, the exposed edge portions of which are movable with relation to the body of the horn and which is adapted in all operative positions to form an even continuation of the general shape of the body of the horn, and independent flexible means adapted to prevent the formation of an air-gap between said earpiece and the body of said horn.

11. In telephony, in combination, receiving mechanism, transmitting mechanism, a

4-
 mouthpiece in operative relation to said transmitting mechanism, and a sound-amplifying horn extending from said receiving mechanism in an unbroken curve of substantially uniformly increasing diameter, said horn comprising an earpiece the exposed edge portions of which are movable with relation to the body of the horn and which is adapted in all operative positions to form an even continuation of the general shape of the body of the horn, and means upon said horn adapted to prevent the entry of foreign matter therein.

12. In telephony, in combination, receiving mechanism comprising a diaphragm, transmitting mechanism, a mouthpiece in operative relation to said transmitting mechanism, and a sound-amplifying horn extending directly from said diaphragm in an unbroken curve of substantially uniformly increasing diameter, said horn comprising an earpiece, the exposed edge portions of which are non-parallel with respect to the face of said mouthpiece and are movable with relation to the body of said horn and form in all operative positions thereof an even continuation of the general shape of the body of the horn.

13. In telephony, in combination, a portable telephone instrument comprising a support, receiving and transmitting mechanisms mounted upon said support, sound-insulating means interposed between said mechanisms, a sound-amplifying horn extending from said receiving mechanism in an unbroken curve of increasing diameter, a mouthpiece in operative relation to said transmitting mechanism, said horn being adapted to swing with reference to said support, connecting means adapted to be operated upon said horn being swung into operative position, and guiding means adapted to prevent a break in the curve of said horn with said horn in operative position.

45 14. In telephony, in combination, a portable telephone instrument comprising a supporting member, receiving and transmitting mechanisms mounted upon said supporting

member, sound-insulating means between said mechanisms, said receiving mechanism comprising a diaphragm, a mouthpiece in operative relation to said transmitting mechanism, a sound-amplifying horn extending directly from said diaphragm in an unbroken curve of substantially uniformly increasing diameter, said horn being adapted to be swung with relation to said support, connecting means adapted to be operated upon said horn being swung into operative position with the face thereof in non-parallel relation to the face of said mouthpiece, and guiding means adapted to prevent a break in the curved passage through said horn with said horn in operative position.

15. In telephony, in combination, a portable telephone instrument comprising a supporting member, receiving and transmitting mechanisms mounted upon said supporting member, sound-insulating means between said mechanisms, said receiving mechanism comprising a diaphragm, a mouthpiece in operative relation to said transmitting mechanism, a sound-amplifying horn extending directly from said diaphragm in an unbroken curve of substantially uniformly increasing diameter, said horn being adapted to be swung with relation to said support, connecting means adapted to be operated upon said horn being swung into operative position with the face thereof in non-parallel relation to the face of said mouthpiece, guiding means adapted to prevent a break in the curved passage through said horn with said horn in operative position, said horn comprising an earpiece the edge portions of which are movable with relation to the body of the horn and in all operative positions form an even continuation of the general shape thereof.

In testimony whereof I affix my signature in the presence of two witnesses.

SAMUEL P. LEVENBERG.
